Inventor:
Alfred Schickerling,

By his Attorney, Geo. F. Heath

UNITED STATES PATENT OFFICE.

ALFRED SCHICKERLING, OF SCARSDALE, NEW YORK.

IDENTIFICATION-CARD CASE.

Application filed July 19, 1926. Serial No. 123,424.

My present invention relates to the type of card case disclosed in Letters Patent of the United States, No. 976,605 granted to me November 22nd, 1910, and designed primarily as a closable receptacle for means of individual identification to be carried upon the person, as for instance, lodge or fraternity cards or certificates, passes, tickets, passports, etc.,—the object of these improvements being to simplify, cheapen, and render more compact and effective the construction and arrangement of the component parts of the device, while providing for the inclusion therein, not only of a card or certificate of the character designated, but also of a photograph of the owner so as to insure positive identification upon occasion, all as hereinafter fully set forth and described and claimed specifically.

In the accompanying drawings I illustrate a practical embodiment of the essential features of my invention in an identification card case or certificate holder of the character designated, although I do not limit myself to the identical configuration of component parts shown herein by way of exemplification, since changes in minor details may be made, and equivalent mechanical expedients resorted to, with like results, and without departing from the spirit and intent of my invention in this respect.

With this understanding:

Fig. 1, represents a side elevation of my identification holder, closed;

Fig. 2, an elevation of the same as opened up and extended lengthwise, showing the interior structure without the insert;

Fig. 3, is a view similar to Fig. 2, showing a portrait card partly inserted in its frame;

Fig. 4, is a transverse section taken upon plane of line 4—4, Fig. 3;

Fig. 5, is a view similar to Figs. 2 and 3, showing a certificate sheet inserted in its holding means preparatory to folding;

Fig. 6, is a transverse section taken upon plane of line 6—6, Fig. 5;

Fig. 7, is a view similar to Fig. 2, but with the portrait card and certificate slip in their proper relative positions, the certificate slip being doubly folded preparatory to the closure of the case, as in Fig. 1.

Fig. 8, is a longitudinal section taken upon plane of line 8—8, Fig. 7, but upon an enlarged scale, and with thicknesses augmented to more clearly illustrate the func-

tion and use of the device, considered in a unitary sense.

It is to be understood that by the term "identification card" as herein used I intend to include any form of foldable card or certificate of a personal character, adapted to be doubled twice upon itself, thereby decreasing its compact form to one fourth of full size, as in my aforesaid Letters Patent No. 976,605, but in the construction of case shown in said Letters Patent both of the hinged sections of the holder are occupied by the folded card, whereas in my present construction and arrangement of parts only one section of the holder is necessary for the accommodation of the folded identification card, the other section of the case being utilized as a frame and support for a photograph or picture of the individual to whom the card or certificate refers.

My new identification case, considered in a unitary sense, consists of two basic cover sections A, B, hinged together at their conjunctive transverse edges so as to be turnable as related to each other on the common pindle *h*, (see Fig. 7). Each of these sections A, B, comprises a basic plate the edges of which are inturned to form a flange circumscribing a dish-shaped depression for the accommodation of a card or folded certificate as hereinafter set forth.

Thus the left hand section A, designed for the accommodation of the certificate C, is formed with an inturned flange *a*, creating a tray for the reception of one of the quadruple folds of the certificate C, which is held in place therein by means of a retaining plate *a'*, soldered or otherwise secured rigidly to the outer end edge and to one longitudinal edge of the flange *a*, as shown more particularly in Figs. 2, 3 and 5, of the drawings. This retaining plate *a'*, overlaps the quarter fold of the certificate C, as positioned in the section A, of the holder, and is formed with a transverse extension *a*², adjacent to the inner end of the section and constituting a straight edge and guide for the final fold of the certificate, and also with a longitudinal extension *a*³, adjacent to the otherwise open lower longitudinal edge of said section A, and constituting a straight edge and guide for the preliminary or medial longitudinal fold of the certificate C, as will be understood by reference more particularly to Fig. 5, of the drawings. These two extensions *a*², *a*³, of the retain-

ing plate a' , facilitate the accurate folding of the certificate C, and function also to hold the folded certificate in proper aligned position within and upon what may thus be 5 designated as the certificate section A, of the holder.

What may hence be designated by way of comparison, as the portrait section B, of the holder, consists essentially of a tray formed 10 with a circumscribing inturned flange b , to the outer end and longitudinal edges of which is rigidly secured a retaining frame plate b' , for engagement with the edges of a card P, bearing a photograph or portrait 15 of the individual whose signature is upon the certificate C, so as to establish absolute identification of the individual upon occasion.

The open inner extremity of the portrait 20 retaining frame plate b' , is preferably formed with a transverse member b^2 , adjacent to the inner end of the section B, although this cross member b^2 , is not absolutely essential, since the edges of the portrait card P, may obviously be inserted 25 under and held in place by the longitudinal and end members of the frame.

The two sections A, B, are held in closed 30 relationship by means of a snap tongue on one part engaging with a corresponding

notch on the other part, as for instance, by the snap tongue b^3 , on the outer end of the portrait section B, fitting in the notch a^4 , formed for the purpose in the outer end of the certificate section C, in the arrangement 35 shown in the drawings, which also show the said ends of the sections provided with finger balls b^4 , and a^5 , to facilitate the opening of the holder. An eyelet or loop h' , may also be provided on a knuckle of the 40 hinge, whereby the holder may be attached to a chain.

What I claim as my invention and desire to secure by Letters Patent, is:—

As an article of manufacture, a foldable 45 identification card case of the character designated, comprising a certificate section and a portrait section hinge-connected, the certificate section consisting of a flanged tray having an integral retaining plate formed 50 with lateral and longitudinal straight edge fold extensions for engagement with a certificate, said lateral extension being disposed adjacent the hinge, and the portrait section consisting of a flanged tray formed with a 55 card retaining frame integral therewith, substantially in the manner and for the purposes set forth.

ALFRED SCHICKERLING.
